UNITED STATES PATENT OFFICE.

ARTHUR ADELMAN, OF CHESANING, MICHIGAN.

FUSE FOR PROJECTILES.

Application filed July 28, 1927. Serial No. 209,093.

(GRANTED UNDER THE PROVISIONS OF THE ACT OF MARCH 3, 1883, 22 STAT. L., 625.)

The invention described herein, may be manufactured and used by or for the Government for governmental purposes without the payment to me of any royalty thereon.

5 The subject of this invention is a fuse for projectiles.

The type of instantaneous elongated fuse designed to burst a shell above the ground functions by direct action on impact of the 10 head of the fuse. At short ranges the axis of the projectile, at the time of impact may make such a small angle with the target on which impact is obtained, usually the surface of the ground, that the impact is not 15 obtained on the head of the fuse. Under such conditions this type of fuse would not function reliably. This depends on the angle of fall to secure operation of the fuse reduces its flexibility in meeting tactical 20 requirements and in the 75 m/m caliber gun of ordinary muzzle velocity and trajectory the minimum range prescribed for this fuse is approximately 3500 yards.

The purpose of the present invention is to 25 refashion existing fuses of the foregoing description in order to include a feature which will permit functioning on graze impact and thereby remove the minimum range limitation.

30 With the foregoing and other objects in view, my invention resides in the novel arrangement and combination of parts and in the details of construction hereinafter described and claimed, it being understood that changes in the precise embodiment of the invention herein disclosed may be made 35 within the scope of what is claimed without departing from the spirit of the invention.

40 A practical embodiment of the invention is illustrated in the accompanying drawing, wherein:

Fig. 1 is a longitudinal sectional view of 45 a fuse constructed in accordance with the invention;

Fig. 2 is a similar view showing the parts in armed position;

Figs. 3 and 4 are detail sectional views on the respective lines of Fig. 1.

50 Referring to the drawings by numerals of reference:

The fuse comprises an elongated body 5 threaded as at 6, for attachment to a shell

and formed with an axial passage 7 for establishing a means of communication between front detonator 8 and a rear detonator 9. This passage is normally interrupted by an inclined transverse plunger 10 which is moved clear of the passage under the influence of centrifugal force during the 60 flight of the shell.

The direct action element of the firing mechanism is embodied in a firing pin or striker 11 which is held against relative movement with respect to the fuse body by 65 a pin 12, shearable on impact, and also by means of a bore safe device consisting of half blocks 13 embracing the firing pin and held together by a spiral 14 having a weighted end 15. The blocks and spiral are 70 confined between the head 16 of the striker and a washer 17 freely mounted on the pin directly in front of the fuse body.

The spiral is normally prevented from unwinding by means of a sleeve 18 slidably mounted on the fore part of the body and held in inoperative position by means of a pin 19 which is sheared on set-back. Upon withdrawal of the sleeve the spiral is 75 unwound due to the action of centrifugal force 80 and the blocks are permitted to break away.

The indirect action element of the firing mechanism comprises an inertia plunger 20 which carries the front primer detonator 8 85 and extends forward around the striker terminating at the extremity of the fuse body and being restrained against forward movement by the bore safe device consisting of the washer 17, half blocks 13 and spiral 14. 90 A spring 21 interposed between the plunger and the rigidly held firing pin serves to prevent forward movement of the plunger during flight after the spiral and blocks are removed. The plunger is formed with slots 95 22 accommodating the shear pin 12 and enabling it to have unobstructed forward displacement.

In the event of a graze impact the plunger will, due to its inertia, move against the action of the spring and will thus cause actuation of the firing mechanism.

The incorporation of the plunger in a direct action fuse of the type specified is thus made without material alteration of its 105 structure and the plunger is held to the in-

operative position by the safety feature already present in the fuse.

I claim:

A fuse including a body, a striker mounted in the forward end of the body, a shear pin securing the striker to the body, a washer slidably mounted on the striker forwardly of the body, safety means removable during flight interposed between the washer

and striker head, means releasable on setback for normally holding the safety means in place, a plunger in the body extending forwardly around the striker and terminating adjacent the washer, a primer carried by the plunger and a spring between the striker and plunger. 10 15

ARTHUR ADELMAN.
